ATTORNEYS.

UNITED STATES PATENT OFFICE.

VERIAN W. SPEARS, OF GREENWOOD, INDIANA.

TELEPHONE CONNECTION.

Application filed March 28, 1924. Serial No. 702,551.

To all whom it may concern:

Be it known that I, VERIAN W. SPEARS, a citizen of the United States, and a resident of Greenwood, county of Johnson, and State 5 of Indiana, have invented a certain new and useful Telephone Connection; and I do hereby declare that the following is a full, clear, and exact description thereof, reference being had to the accompanying drawings, in which like numerals refer to like parts.

This invention relates to a telephone connection and particularly the plug and the terminal arrangement associated therewith. 15 The chief object of the invention is to provide a telephone connection which includes a plug for simultaneously closing a circuit through two separated terminals and for providing an adjustable normally open circuit which is grounded for protective purposes.

The chief feature of the invention consists in the particular construction of the connecting plug; and another feature of the invention 25 consists in the arrangement and mounting of the terminals engageable by said plug.

The full nature of the invention will be understood from the accompanying drawings and the following description and 30 claims:

In the drawings, Fig. 1 is a front elevational view of the aforesaid connection including the lug and terminals and the mounting therefor. Fig. 2 is a side elevational view thereof. Fig. 3 is a front elevational view of the terminal plug. Fig. 4 is a side elevational view thereof.

In the drawings, Fig. 1 indicates a suitable post, standard, support or building side. 40 Suitably mounted thereon, as by means of the screws 11 and spacers or insulated bushings 12 is a supporting plate 13. Said plate carries an open-work housing or protective covering indicated generally by the numeral 14, the sides of which are apertured as at 15 to provide a pair of openings in alignment with each other. The backplate 13 is also apertured as at 16 and securely mounted therein is a forwardly projecting pin 17 which is connected upon the rear of the backplate 13 to a grounded current conductor or ground wire 18. Positioned in each of the openings 15 are a pair of identical but oppositely positioned insulated bushings 19 which insulate a pair of L-shaped terminal bolts 20 having the angular ends 21 from

the housing or sides and which are adjustably supported thereby, by means of the nuts 22. Each L-shaped terminal bolt is connected to a current conducting line 23 by means of another nut 24. Thus, the current carrying lines are brought into the housing from opposite directions. As shown clearly in Figs. 1 and 2, an insulation plate 25 is socketed as at 26, and positioned in or anchored by said sockets are the angular ends 21 of the L-shaped terminals 20. Said plate is suitably secured to the backplate 13 as shown in Fig. 1. From the foregoing, therefore, it will be noted that there are three parallel contact or cylindrical surfaces arranged triangularly with respect to each other.

Reference will now be had to Figs. 3 and 4, wherein the plug portion of the connection 75 is particularly illustrated. In this form of the invention there is provided an insulated handle 30 which supports a protective conduit 31 or equivalent construction carrying the current conducting wires 32. Positioned within the tubular handle 30 is an insulation base 33 which may be formed in any desired manner, and herein is illustrated as of a single piece provided with a longitudinally extending slot 34 which extends 80 but partially through the same. The plug 33 is also provided with a pair of oppositely positioned grooves 35 transversely positioned with respect to said slot or groove 34. There is also provided a pair of recesses 36 90 which are oppositely positioned with respect to each other and communicate with each other by a transversely positioned opening 37 that communicates with the groove or slot 34. A similar transversely positioned opening 38 therebeneath also communicates with said groove. In the groove or slot 34, there is positioned a pair of spring members 39 which have openings 40 and 41 adapted to receive respectively a bolt construction 42 100 and a pin 43 for locking or anchoring said spring contacts 39 in the groove or slot 34. The outer and free ends of said spring members are provided with a curved portion 44 and a contact extension 45. The arrangement is such, as shown in Figs. 1 and 3, that the contact portions 45 straddle or bear upon opposite sides of the contact pin 17, thereby completing a ground connection from the spring terminal members 39 to the ground 105 wire 18.

Herein since the other contact construc-

tions are similar, a description of one will be given whereby an understanding will be had of both. This construction is a spring contact member 46 having an angular 5 curved extension 47 adapted to bear upon the inner surface of the angular extension 21 of the terminal 20. Each of the terminal members 46 is offset at 48 to form a U-shaped portion seatable in the groove 35. 10 The spring clips 46 are suitably secured to the insulation base or block 33 by suitable means such as the screws 49. The other end of the spring member projects laterally and downwardly as at 50 beneath the block and 15 is suitably connected as indicated at 51 to one of the current conducting wires 32. Thus, a circuit may be completed from one wire 23 through the terminal bolt 20, angular extension 21 thereof, thence through the 20 contact member 26 to the other end 50 thereof and through one current conducting wire 32 to the other current conducting wire 32, and thence in reverse order to other similar parts and to the other terminal wire 23 and 25 the wires 32 being stationarily mounted.

The plug 33 is suitably apertured at 52 which is transversely positioned with respect to the groove 35 and the slot 34, and in axial alignment with both. Each of the U-shaped portions 48 adjustably supports a contact screw 53 adjustably and lockingly secured in adjusted position by the nut 54. The free end of the contact bolt 53 terminates adjacent the spring member 39 at the 35 junction of the slot 34 and transversely positioned opening 52, whereby there is formed between the same an air gap. The other contact bolt 53 is similarly mounted in adjusted position whereby there is provided 40 another air gap of the desired width between the contact clip 46 and the grounding clip 39.

The invention claimed is:

1. In a telephone connection, the combination of a pair of L-shaped terminal bolts 45 positioned with their angular extensions in

parallel relation and their body portions extending in opposite directions, and a third terminal member positioned intermediate the angular extensions and parallel thereto. 50

2. In a telephone connection, the combination of a pair of L-shaped terminal bolts positioned with their angular extensions in parallel relation and their body portions extending in opposite directions, and a third terminal member positioned intermediate the angular extensions and parallel thereto and in a plane other than the plane including the angular extensions and substantially in triangular relation therewith. 55 60

3. A telephone connection including a base, a grounding connection supported thereby, a pair of current carrying members supported by said base and insulated from each other and the grounding connection, 65 said grounding connection being positioned between said current carrying members, and a potential gap construction interposed between each of the current carrying members and the grounding connection. 70

4. A telephone connection including a base, a grounding connection supported thereby, a pair of current carrying members supported by said base and insulated from each other and the grounding connection, 75 said grounding connection being positioned between said current carrying members, and an adjustable potential gap construction interposed between each of the current carrying members and the grounding connection. 80

5. A telephone connection plug including a pair of longitudinally extending oppositely positioned diverging terminal members, and a longitudinal grounding connection positioned midway therebetween and comprising a pair of inwardly directed members normally separable when in current conducting position. 85

In witness whereof, I have hereunto affixed my signature.

VERIAN W. SPEARS.
